UNITED STATES PATENT OFFICE

LOUIS A. MAXSON, OF CLAREMONT, NEW HAMPSHIRE, ASSIGNOR TO SULLIVAN MACHINERY COMPANY, A CORPORATION OF MASSACHUSETTS

MINING APPARATUS

Application filed January 17, 1929, Serial No. 333,080. Renewed May 23, 1930.

This invention relates to mining apparatus and more particularly to coal mining apparatus of the swinging cutter bar type having improved means for effecting bar swing.

An object of this invention is to provide an improved mining apparatus. Another object is to provide an improved coal mining apparatus of the pivoted cutter bar type having improved swinging means for effecting bar swing. A further object is to provide improved kerf cutting mechanism of the pivoted cutter bar type having improved plural speed swinging mechanism for the cutter bar whereby the latter may be swung about its pivotal axis at a slow cutting speed and at a relatively high bar positioning speed. A further object is to provide in a mining apparatus of the aforesaid type improved bar swinging mechanism wherein the fast speed swing occurs in one direction and the slow speed swing in the opposite direction. These and other objects of this invention will, however, subsequently more fully appear as the description proceeds.

In the accompanying drawings there is shown for purposes of illustration one embodiment which the invention may assume in practice.

In these drawings,—

Fig. 1 is a top plan view, partially broken away in horizontal section to illustrate details of construction, of the improved kerf cutting mechanism.

Fig. 2 is a transverse vertical sectional view taken substantially on line 2—2 of Fig. 1.

Fig. 3 is a central longitudinal vertical sectional view taken substantially on line 3—3 of Fig. 1.

Fig. 4 is a detail sectional view taken on line 4—4 of Fig. 1.

Fig. 5 is an enlarged detail sectional view illustrating the improved speed controlling clutch device.

In this embodiment of the invention the same is shown for purposes of illustration incorporated with the kerf cutting mechanism generally designated 1 of a coal mining apparatus which is herein of the so-called "universal" cutter type adapted to operate from the mine trackway and is here-

in of the same general construction as that described in a copending application of one Morris P. Holmes, Serial No. 6,477, filed February 2, 1925 now matured into Patent No. 1,786,243, patented Dec. 23, 1930. The kerf cutting mechanism 1 in this instance comprises a rotatable cutter head frame 2 having a pivotal bearing 3 about a horizontal longitudinal axis on the body 4 of the mining apparatus, the cutter head frame being rotatable about its pivotal axis through connections which may assume the form of those described in the aforesaid application from the power shaft 5 of the driving motor of the apparatus. The driving motor is herein preferably of the reversible electric type and its power shaft 5 is horizontally disposed and extends longitudinally of the apparatus and projects axially through the pivotal bearing 3 for the rotatable cutter head frame. As shown in Fig. 3, fixed to the forward end of the motor shaft and rotatable therewith is a toothed clutch member 6 connectible by an operator-controlled shiftable toothed clutch member 7 to a toothed clutch member 8 secured to a shaft 9 aligned with the motor shaft 5 and suitably journaled within the cutter head frame. Herein formed integral with the shaft 9 is a bevel pinion 10 meshing with a bevel gear 11 secured to and rotatable with a transverse shaft 12 likewise suitably journaled within the cutter head frame. Also rotatable with the shaft 12 is a spur pinion 13 meshing with a large spur gear 14 having its hub portion journaled on ball bearings 15 supported by a transverse shaft 16 suitably journaled within the cutter head frame. The hub portion of the spur gear 14 is connected by a semi-permanent clutch 17 to a clutch member 18 journaled on a bearing sleeve supported by the shaft 16. The clutch member 18 is connectible by an operator-controlled shiftable clutch member 19 to a clutch member 20 keyed at 21 to the shaft 16. Keyed at 22 to one end of the shaft 16 is a drive sprocket 23 which engages and drives an endless cutter bit carrying cutter chain 24 movable in an orbit about the outer edges of an elongated plane cutter bar 25. It will thus be seen that when the clutches 6, 7, 8

and 18, 19, 20 are connected the cutter chain may be driven from the motor and that the cutter chain may be disconnected from the motor at will by the clutch 18, 19, 20 while 5 the gear 14 continuously rotates.

In this illustrative embodiment of the invention the cutter bar 25 is shown having a pivotal bearing on the cutter head frame for swinging movement relative thereto about an 10 axis coincident to the axis of the drive shaft 16. As shown, the cutter bar 25 has fixed thereto by screws 26 a ring-like member 27 having an annular bearing surface engaging a thrust ring 28 secured by screws 29 to the 15 cutter head frame 2, the cutter bar also having formed integral therewith a radial flange 30 having an annular bearing surface engaging the opposite side of the thrust ring. Also, as shown in Fig. 3, secured to the cutter 20 bar 25 by screws 31 is a cylindrical bearing member 32 surrounding the drive shaft 16 and journaled in a bearing sleeve 33 supported by a cylindrical bearing portion 34 of the cutter head frame.

25 The improved mechanism for effecting swinging movement of the cutter bar about its pivotal axis relative to the cutter head frame herein comprises a spur pinion 35 meshing with the spur gear 14, the axes of 30 the gears 35 and 14 lying in a common transverse vertical plane. This spur pinion is keyed at 36 to a transverse shaft 37 arranged parallel with the shaft 16 and journaled in ball bearings 38 suitably supported within 35 the cutter head frame 2. The shaft 37 has fixed thereto at 39 a worm 40 meshing with a worm wheel 41. This worm wheel 41 is journaled on a ball bearing 42 supported by a sleeve member 43 keyed at 44 to a horizontal drive shaft 45 extending transversely of the cutter head frame and journaled at its 40 ends in ball bearings 46 supported thereby. As illustrated, the worm wheel 41 carries a series of clutch discs 48 which are interleaved 45 with a corresponding series of clutch discs 49 carried by the sleeve 43. The means for applying the clutch 48, 49 to connect the sleeve 43 to the worm wheel 41 comprises a pressure plate 50. Threadedly connected 50 within the side of the cutter head frame is a pressure screw 51 to press the pressure plate 50 and having a suitable operating handle 52. It will thus be evident that when the pressure screw 51 is screwed inwardly 55 the pressure plate 50 is forced axially inwardly, thereby pressing the friction discs into frictional driving engagement.

60 In this illustrative form of the invention a spur gear 54 is shown formed integral with the shaft 45 and meshing with a plurality of spur gears 55, herein three, journaled on studs 56 fixed at 57 to a rotatable spider member 58 journaled on a member 58^a keyed to the shaft 45. Meshing with the gears 55 is 65 an internal gear 59 having its hub portion

journaled within a ball bearing 60 and rigidly fixed at 61 to a hollow sleeve or shaft 62 through which the main driving shaft 45 extends. This shaft 62 is journaled in suitable bearings 63 formed within the cutter head frame. Herein formed integral with the hollow drive shaft 62 intermediate its ends is a worm 64 meshing with a worm gear 65 (see also Fig. 3) keyed to a clutch member 66 rotatably mounted on a transverse shaft 67 arranged parallel with the drive shaft 16 and likewise suitably journaled within the cutter head frame. The clutch member 66 is connectible by an operator-controlled clutch member 68 to a clutch member 69 keyed at 70 to the shaft 67. Herein formed integral with the shaft 67 at one end thereof is a spur pinion 71 meshing with an internal gear 72 formed integral with the bearing support 27 for the cutter bar.

An improved clutch device generally designated 75 is employed for controlling the speed of rotation of the worm shaft 62 and herein comprises a clutch member 76 slidably mounted on the shaft 45 and having clutch teeth 77 interlocked with clutch teeth 78 formed on the hub of the pinion supporting spider 58. As more clearly shown in Fig. 5, it will be observed that the clutch member 76 has clutch teeth 79 and 80 which are alternatively connectible to clutch teeth 81 and 82 carried by the member 58^a keyed to the shaft 45 and cutter head frame 2 respectively. It will thus be evident that when the clutch member is shifted inwardly from the position shown in Figs. 1 and 5, the pinion supporting spider 58 is clutched directly to the member 58^a keyed to the shaft 45 while when the clutch member is shifted in the opposite direction, i. e., the position shown in Fig. 5, the pinion supporting spider 58 is held against rotation relative to the cutter head frame.

The operator-controlled means for shifting the clutch member 76 herein comprises an actuating rod 83 mounted for endwise movement in a bore 84 extending centrally through the drive shaft 45. This operating rod 83 has fixed thereto at its opposite ends at opposite sides of the cutter head suitable operating handles 85. A spring pressed plunger 86 carried by the cutter head frame is engageable with spaced grooves on the operating rod and is employed to hold the latter in its different axially adjusted positions. Fixed to and extending transversely of the operating rod 83 is a pin 87 having its ends projecting through longitudinal slots 87^a in the shaft 45 within an annular groove 88 formed internally within the clutch member 76. It will be evident that this pin and groove connection between the operating rod and clutch member permits the shaft 45 to rotate freely relative thereto while still enabling the clutch member to be shifted axially relative to the shaft at will.

The operating mechanisms for the shiftable clutch members 7, 19, and 68 are of a type similar to those described in the above mentioned application of Morris P. Holmes and as these operating means do not specifically reside in this invention further description of the same is deemed unnecessary.

The operation of the improved means for effecting swinging movement of the cutter bar about its pivotal axis is as follows. When it is desired to swing the cutter bar 25 transversely in its plane at a fast bar positioning speed the operator first actuates the clutch member 7 connecting the drive gearing 10, 11, 13, and 14 to the motor shaft 5. The clutch member 68 is then shifted axially connecting the worm wheel 65 to the shaft 67. The operator then grasps one of the operating handles 85 and slides the operating rod 83 inwardly from the position shown in Fig. 5, thereby shifting the clutch member 76 to connect the clutch teeth 79 thereon with the teeth 81 on the member 58a keyed to the shaft 45, the teeth 80 on the clutch member being released from the teeth 82 on the cutter head frame at that time. The operator then grasps the operating handle 52 and applies the clutch 48, 49 connecting the worm wheel 41 in frictional driving engagement with the shaft 45 to effect rotation of the latter. Rotation of the shaft 45 is transmitted to the spur pinion 54 turning the same together with the pinions 55 and internal gear 59 which are at that time locked to the shaft 45 by the engagement of the clutch teeth on the clutch member 76 with the teeth on the shaft. As a result, rotation of the shaft 45 is transmitted directly to the worm 64 rotating the latter in the same angular rate therewith at a fast speed. The worm 64 drives the worm wheel 65 and spur pinion 71, which meshes with internal gear 72 connected to the cutter bar, thereby effecting swinging movement of the cutter bar relative to the cutter head frame at a relatively high bar positioning speed. When it is desired to effect bar swing at a relatively slow cutting speed in the opposite direction, the operator grasps the handle 85 and shifts the clutch member 76 to the position shown in Figs. 1 and 5, thereby connecting the pinion supporting spider 58 to the cutter head frame by engagement of the teeth 80 on the clutch member 76 with the teeth 82 on the frame. Upon application of the friction clutch within the worm wheel 41 the shaft 45 together with the gear 54 is rotated, the latter meshing with the gears 55 rotating the same about their then stationary axes, thereby causing rotation of the internal gear 59 at a reduced speed, the slow rotation of the internal gear 59 being transmitted through the shaft 62, worm 64, worm wheel 65, and pinion 71 meshing with the internal gear 72 to the cutter bar, thereby effecting swinging movement of the latter at a rela-

tively slow cutting speed in an opposite direction from the fast speed bar swing described above. It is also evident that when the clutch member 76 is shifted into its intermediate or neutral position both fast and slow speed swinging mechanisms are disconnected from the worm wheel 41, the worm gearing 64, 65 being self-locking thereby holding the cutter bar against swinging movement relative to the cutter head frame at that time. It will further be evident that when the clutch member 19 is shifted to a position to connect the clutch members 18 and 20 together the cutter chain 24 may be driven from the motor shaft at will during either direction of bar swing. These and other operations of the improved bar swinging mechanism will be clearly apparent to those skilled in the art.

As a result of this invention it will be noted that an improved and simplified bar swinging mechanism is provided which is driven through a simple and compact gear train directly from the cutter chain driving gear, only a single worm gear train being employed in the plural speed drive for swinging the cutter bar at either of its speeds. It will further be noted that by employing the gearing together with the controlling clutch device therefor, simple mechanism is attained wherein a plurality of speeds, i. e. a slow cutting and a relatively high bar positioning speed, are provided. It will still further be noted that the bar swinging mechanism provided is of simple, rugged, and compact design readily applicable to a mining machine of standard construction with a minimum of change and expense and further readily adapted to withstand the severe conditions of service encountered in a mine.

While there is in this application specifically described one form which the invention may assume in practice, it will be understood that this embodiment of the same is shown for purposes of illustration and that various other modifications and embodiments may be used without departing from its spirit or the scope of the appended claims.

What I claim as new and desire to secure by Letters Patent is:

1. In a mining apparatus, kerf cutting mechanism including a pivoted cutter bar, and motor driven mechanism for effecting bar swing at a slow cutting speed and at a relatively fast bar positioning speed comprising a driving gear, a shaft coaxial with and extending through said gear, a controlling clutch for connecting said shaft to said gear, a second gear coaxial with said shaft and operatively connected to said cutter bar, said shaft extending through said second gear, and plural speed mechanism between said shaft and said second gear for driving the latter at a plurality of speeds, said plu-

ral speed mechanism lying wholly at one side of said second gear.

2. In a mining apparatus, kerf cutting mechanism including a pivoted cutter bar, and motor driven mechanism for effecting bar swing at a slow cutting speed and at a relatively fast bar positioning speed comprising a driving gear, a shaft coaxial with and extending through said gear, a controlling clutch for connecting said shaft to said gear, a second gear coaxial with said shaft and operatively connected to said cutter bar, and plural speed mechanism between said first and said second gears for driving said second gear at a plurality of speeds, said plural speed mechanism being disposed at the opposite side of said second gear from said clutch.

3. In a mining apparatus, kerf cutting mechanism including a pivoted cutter bar, and motor driven mechanism for effecting bar swing at a slow cutting speed and at a relatively fast bar positioning speed comprising a driving gear, a shaft coaxial with and extending through said gear, a controlling clutch for connecting said shaft to said gear, a second gear coaxial with said shaft and operatively connected to said cutter bar, and plural speed mechanism between said first and said second gears for driving said second gear at a plurality of speeds, said plural speed mechanism being disposed coaxially with and at the opposite side of said second gear from said clutch.

4. In a mining apparatus, kerf cutting mechanism including a pivoted cutter bar, and motor driven mechanism for effecting bar swing at a slow cutting speed and at a relatively fast bar positioning speed comprising a worm wheel, a shaft coaxial with and extending through said worm wheel, a controlling clutch for connecting said shaft to said worm wheel, a worm coaxial with said shaft and operatively connected to said cutter bar, and plural speed mechanism between said worm wheel and said worm for driving the latter at a plurality of speeds.

5. In a mining apparatus, kerf cutting mechanism including a pivoted cutter bar, and motor driven mechanism for effecting bar swing at a slow cutting speed and at a relatively fast bar positioning speed comprising a worm wheel, a shaft coaxial with and extending through said worm wheel, a controlling clutch for connecting said shaft to said worm wheel, a worm coaxial with said shaft and operatively connected to said cutter bar, and plural speed mechanism between said worm wheel and said worm for driving the latter at a plurality of speeds, said plural speed mechanism being disposed at the opposite side of said worm from said clutch.

6. In a mining apparatus, kerf cutting mechanism including a pivoted cutter bar,

and motor driven mechanism for effecting bar swing at a slow cutting speed and at a relatively fast bar positioning speed comprising a worm wheel, a shaft coaxial with and extending through said worm wheel, a controlling clutch for connecting said shaft to said worm wheel, a worm coaxial with said shaft and operatively connected to said cutter bar, and plural speed mechanism between said worm wheels and said worm for driving the latter at a plurality of speeds, said plural speed mechanism being disposed coaxially with and at the opposite side of said worm from said clutch.

7. In a mining apparatus, kerf cutting mechanism including a pivoted cutter bar, and motor driven mechanism for effecting bar swing at a slow cutting speed and at a relatively fast bar positioning speed comprising a driving gear, a shaft coaxial with and extending through said gear, a controlling clutch for connecting said shaft to said gear, a second gear coaxial with said shaft and operatively connected to said cutter bar, and plural speed mechanism between said first and second gears for driving said second gear at a plurality of speeds, said plural speed mechanism being disposed at the opposite side of said second gear from said clutch and comprising a clutch device for connecting a rotatable part of said plural speed mechanism to a stationary abutment or for connecting relatively rotatable parts thereof together for simultaneous rotation.

8. In a mining apparatus, kerf cutting mechanism including a pivoted cutter bar, and motor driven mechanism for effecting bar swing at a slow cutting speed and at a relatively fast bar positioning speed comprising a driving gear, a shaft coaxial with and extending through said gear, a controlling clutch for connecting said shaft to said gear, a second gear coaxial with said shaft and operatively connected to said cutter bar, and plural speed mechanism between said first and second gears for driving said second gear at a plurality of speeds, said plural speed mechanism being disposed at the opposite side of said second gear from said clutch and including a clutch device arranged coaxially with said second gear for connecting a rotatable part of said plural speed mechanism to a stationary abutment or for connecting relatively rotatable parts thereof together for simultaneous rotation.

9. In a mining apparatus, kerf cutting mechanism including a pivoted cutter bar, and motor driven mechanism for effecting bar swing at a slow cutting speed and at a relatively fast bar positioning speed comprising a driving gear operatively connected to said bar, and means for driving said gear at fast and slow speeds including a controlling clutch disposed coaxially with said gear at one side thereof, plural speed gearing at

the other side of said gear for driving the latter at a plurality of speeds, and a drive shaft extending coaxially through said gear between said clutch and said plural speed 5 gearing for transmitting drive from the clutch to said plural speed gearing.

10. In a mining apparatus, kerf cutting mechanism including a pivoted cutter bar, and motor driven mechanism for effecting 10 bar swing at a slow cutting speed and at a relatively fast bar positioning speed comprising a driving gear operatively connected to said bar, and means for driving said gear at fast and slow speeds including a controlling 15 clutch disposed coaxially with said gear at one side thereof, plural speed gearing at the other side of said gear, and a drive shaft extending coaxially through said gear between said clutch and said plural speed gearing, said plural speed gearing including a clutch device for holding an element of said gearing stationary or for permitting free rotation thereof.

11. In a mining apparatus, kerf cutting 25 mechanism including a pivoted cutter bar, and motor driven mechanism for effecting bar swing at a slow cutting speed and at a relatively fast bar positioning speed comprising a driving gear operatively connected to said bar, and means for driving said gear at fast and slow speeds including a controlling 30 clutch disposed coaxially with said gear at one side thereof, plural speed gearing at the other side of said gear, and a drive shaft extending coaxially through said gear between said clutch and said plural speed gearing, said plural speed gearing including a clutch device for holding an element of said gearing stationary or for permitting 35 free rotation thereof and for connecting relatively rotatable elements of said gearing together for simultaneous rotation.

12. In a mining apparatus, kerf cutting mechanism including a pivoted cutter bar, 45 and motor driven mechanism for effecting bar swing at a slow cutting speed and a relatively fast bar positioning speed comprising a driving gear operatively connected to said bar, a gear coaxial therewith, means for connecting said second mentioned gear to said 50 first mentioned gear to effect drive of the latter at fast and slow speeds including a controlling clutch disposed coaxially with said gears at one side thereof, plural speed gearing 55 at the other side of said gears and including a clutch device coaxial with said gears, and a drive shaft extending coaxially through said gears between said controlling clutch and said plural speed gearing for transmitting drive from the clutch to said plural speed gearing.

13. In a mining apparatus, kerf cutting 60 mechanism including a pivoted cutter bar, and motor driven mechanism for effecting bar swing at a slow cutting speed and at a

relatively high bar positioning speed comprising a worm operatively connected to said cutter bar, and means including a worm wheel coaxial with said worm for driving said worm at fast and slow speeds including 70 a controlling clutch disposed coaxially with said worm wheel at one side of said worm, plural speed gearing at the other side of said worm, and a drive shaft extending coaxially through said worm and worm wheel 75 between said clutch and plural speed gearing, said shaft being connectible to said worm wheel by said clutch and to said worm through said plural speed gearing.

14. In a mining apparatus, kerf cutting mechanism including a pivoted cutter bar, and motor driven mechanism for effecting bar swing at a slow cutting speed and at a relatively fast bar positioning speed comprising a worm gear train, a second worm gear train, and plural speed gearing in the drive between said worm gear trains.

15. In a mining apparatus, kerf cutting mechanism including a pivoted cutter bar, 80 and motor driven mechanism for effecting bar swing at a slow cutting speed and at a relatively fast bar positioning speed including coaxially arranged shafts through which bar swing is effected at both speeds, means for driving one shaft, a gear driven by the other shaft, a gear element secured to said cutter bar and with which said gear meshes, a reduction gearing, and means for connecting said shafts directly together to obtain 85 a fast speed drive or to drive one shaft from the other through said reduction gearing to obtain a slow speed drive.

16. In a mining apparatus, kerf cutting mechanism including a pivoted cutter bar, 90 and motor driven mechanism for effecting bar swing at a slow cutting speed and at a relatively fast bar positioning speed including a gear, a coaxial gear, orbitally movable gears meshing with said gears, and driving 95 connections between said coaxial gear and said cutter bar and operatively connected through intermeshing gearing directly to the latter, said orbitally movable gears moving in their orbits to effect fast speed swing and rotating upon fixed axes to effect slow speed 100 swing.

17. In a mining apparatus, kerf cutting mechanism including a pivoted cutter bar, 105 and motor driven mechanism for effecting bar swing at a slow cutting speed and at a relatively fast bar positioning speed including a gear, a coaxial gear and orbitally movable gears meshing with said coaxial gears, and means for causing drive of one coaxial 110 gear by the other through said orbitally movable gears, while the latter rotate upon fixed axes, to obtain a slow speed drive or for connecting all of said gears together for rotation as a unit to obtain a high speed drive.

18. In a mining apparatus, kerf cutting 115

- mechanism including a pivoted cutter bar, and motor driven mechanism for effecting bar swing at a slow cutting speed and at a relatively fast bar positioning speed including a driving gear, a shaft coaxial therewith, a second gear coaxial with said shaft and operatively connected to said cutter bar and reversing and plural speed mechanism between said shaft and said second gear for effecting 10 drive of said second gear by said shaft and including a driving element rotatable in one direction to effect slow speed swing and in the opposite direction to effect high speed swing.
- 15 19. In a mining apparatus, kerf cutting mechanism including a pivoted cutter bar, and motor driven mechanism for effecting bar swing at a slow cutting speed and at a relatively fast bar positioning speed including a 20 driving gear, a shaft coaxial therewith, a second gear coaxial with said shaft and operatively connected to said cutter bar and plural speed mechanism between said shaft and said second gear for transmitting drive to the latter, said plural speed mechanism being arranged at the opposite side of said second gear from said first gear.
- 25 20. In a mining apparatus, kerf cutting mechanism including a pivoted cutter bar, and motor driven mechanism for effecting bar swing at a slow cutting speed and at a relatively fast bar positioning speed including a driving gear, a shaft coaxial therewith, a second gear coaxial with said shaft and operatively connected to said cutter bar, and reversing and plural speed mechanism between said shaft and said second gear for driving the latter, said plural speed mechanism being arranged generally coaxially with said shaft 30 and including a gear rotatable in one direction to effect slow speed swing and in the opposite direction to effect high speed swing.
- 35 21. In a mining apparatus, kerf cutting mechanism including a pivoted cutter bar, and motor driven mechanism for effecting bar swing at a slow cutting speed and at a relatively fast bar positioning speed including a driving gear, a shaft coaxial with said 40 gear, a worm coaxial with said shaft operatively connected to said cutter bar, and plural speed mechanism between said gear and said worm for transmitting drive from the former to the latter, said plural speed mechanism being arranged at the opposite side of said worm from said driving gear.
- 45 22. In a mining apparatus, kerf cutting mechanism including a pivoted cutter bar, and motor driven mechanism for effecting bar swing at a slow cutting speed and at a relatively fast bar positioning speed including a plural speed mechanism comprising a clutch device for connecting a rotatable part thereof to a stationary abutment to obtain 50 one speed or for connecting relatively rotat-

able parts thereof together for simultaneous rotation to obtain a different speed.

23. In a mining apparatus, kerf cutting mechanism including a pivoted cutter bar, and motor driven mechanism for effecting bar swing at a slow cutting speed and at a relatively fast bar positioning speed including a driving gear, a shaft coaxial with said gear, a second gear coaxial with said shaft and operatively connected to said cutter bar, and plural speed mechanism between said first and second gears, said plural speed mechanism being disposed at the opposite side of said second gear from said first gear and comprising a clutch device for connecting a rotatable part of said plural speed mechanism to a stationary abutment or for connecting relatively rotatable parts thereof together for simultaneous rotation.

In testimony whereof I affix my signature. 85
